WINDOW DEVICE FOR GARMENT BAGS
AND LIKE CONTAINERS

William R. Kohl, Glenview, Ill.

Application August 8, 1947, Serial No. 767,448

9 Claims. (Cl. 206—45.31)

1

This invention pertains to an improved inspection window device, particularly devised for application to a garment storage bag, although also well adapted for application to containers of other sorts.

It is a particular object of the invention to provide a simplified window device of the above type having improved provisions to effect a lapped, light-proof sealing closure of a window thereof, thereby to prevent fading of garments stored in a garment bag to which the device is applied.

Another object is to provide a device of the foregoing character, which is readily and quickly applied to the aforesaid garment bags or related types of containers and which affords an inspection window and marginally overlapping closure adapted to be latched in closing and light-sealing relation to the window, yet readily withdrawable manually for inspection of the contents of the container.

The foregoing statements are indicative in a general way of the nature of the invention, but other and more specific objects will be apparent to those skilled in the art upon a full understanding of the construction and operation of the device.

Various embodiments of the invention are presented herein for purpose of exemplification, and it will be appreciated that the invention is susceptible of incorporation in still other modified forms coming equally within the scope of the appended claims.

In the drawings,

Fig. 1 is a face view of a garment storage bag of a well known type having the window device of the present invention applied thereto;

Fig. 2 is an enlarged plan view of the device itself, in open, flat condition, prior to folding and adhesively affixing the same to the bag or like container;

Fig. 3 is a fragmentary face view of the window device as applied to the garment bag;

Fig. 4 is an enlarged fragmentary view in vertical section on a line corresponding to line 4—4 of Fig. 3, illustrating in dotted line the manner of swinging the closure element of the device outwardly for inspection of the contents of the container;

Fig. 5 is a fragmentary view generally similar to Fig. 3, illustrating a modified adaptation of the invention;

Fig. 6 is a view similar to Fig. 2, illustrating the window device of Fig. 5 in its flat condition prior to folding and affixing the same to the container;

2

Fig. 7 is a fragmentary view in section on line 7—7 of Fig. 5, illustrating in dotted line the manner of swinging the closure element of the device outwardly for inspection of the contents of the container;

Fig. 8 is a fragmentary view similar to Figs. 3 and 5, illustrating a still further embodiment of the invention;

Fig. 9 is a bottom plan view of the window device of Fig. 8, illustrating the component parts thereof in assembled relation; and

Fig. 10 is a fragmentary sectional view on a line corresponding to line 10—10 of Fig. 8, the portion thereof in dotted line indicating the manner of swinging the closure element outwardly.

This invention pertains to improvements in an inspection window device or window shield, in a preferred adaptation thereof applied to a conventional garment storage bag. Similar structures are illustrated and described in my Patent No. 2,383,132, of August 21, 1945, and in my co-pending application Serial No. 691,117, filed August 16, 1946, now Patent No. 2,479,627, of August 23, 1949.

In particular, the present improvements deal with a two-ply transparent window and closure device superposed over an opening in the garment bag or like container, including a novel swingable closure flap adapted to be disposed in laterally overlapping relation to the margins of said opening. This eliminates possibility of light leakage through the slit in the device which outline the edges of the flap and the opening in the container, an objectionable feature in previous devices of this character. Moreover, the invention affords a novel means for latching said closure flap in place during storage, yet enabling ready unlatching thereof for outward swinging movement if it is desired to view the contents of the container through the window of the device. A double ply transparent window sheet insures against entry of moths or dust into the container, and this protection is had even though one of the transparent sheets should become ruptured.

Referring to the drawings, and in particular to Figs. 1 to 4 inclusive, the reference numeral 10 generally designates a container to which the device of the invention is applied, being illustrated as a standard paper garment storage bag of which the structural details are so familiar as not to require further explanation. As illustrated in Fig. 4, this container is provided with a viewing opening 11 in the front wall thereof, over which the present window device, generally des-

gnated by the reference numeral 12 is superposed.

This device is fabricated from a flexible fiber or paper board blank 13 of the outline illustrated in Fig. 2, which is subdivided by a medial transverse crease or fold line 14 into outer and inner sections 15, 16, respectively. These are of generally rectangular shape, the former being of substantially greater longitudinal and lateral dimensions than the latter. The sections 15, 16 have the respective opposite, arcuate end margins 17, 18 of which the former is interrupted by a projecting, dovetail-shaped detent or holding tab 19, for a purpose to be hereinafter described.

The inner section 16 is provided with a window opening 20 in an outline generally corresponding to, but of smaller size than that of said section, while the outer section 15 is provided with a substantially U-shaped slit 21 which has rounded, in-turned extremities 22. At its mid-point, slit 21 is extended outwardly at 23 to form a latching tab 24. Slit 21 thereby defines in the section 15 of blank 13 a closure member or panel 25 provided with the latching tab 24 at its free, outwardly swingable marginal extremity, said closure member being of somewhat larger size than, but of the same general shape as, the opening 20 of the other section 16. The window aperture 20 in the inner garment bag abutting section 16 of the device is so located relative to the closure panel 25 in the section 15 that, when the device is folded on itself along transverse line 14, the aperture is substantially overlapped laterally and longitudinally by the panel.

The device is completed by a sheet or sheets of transparent material such as cellophane, said sheet being designated by the reference numeral 26. Its outline generally corresponds to the outline of the device 12 but is of somewhat smaller size, so as to afford a marginal area 27, at least the section 15, for a purpose to be described. Transparent sheet 26 is adhesively secured to the blank 13 to extend across the areas in which opening 20 and closure panel 25 are located, but is not adhered to the latter. It will be apparent that two separate window sheets, one for each of sections 15, 16, could equally well be employed and still accomplish the purposes of the present invention. In fact, a single sheet over the opening 20 would serve, but the double ply transparent window element is preferred, since opening 11 is sealed even if one window ply is broken.

In applying the device to the container, it is first folded on line 14 and in this condition the surface of the section 16 opposite the transparent window sheet 26 is adhesively secured to the face of the bag 10, with opening 20 in aligned relation to the opening 11 of the bag, the fold line 14 being adjacent the top of said opening. A suitable cement or adhesive is, or has been, applied to the marginal area 27 of section 15 which overlaps the window sheet, and said area is then adhesively secured to the body of the container 10. The holding tab 19 is then reversely folded back onto the exposed surface of section 15 and adhesively secured thereto. This may of course be done prior to application of the device to the bag. In any event, when so folded, the tab 19 will vertically overhang the slit 23 and the latching tab 24 to provide a recess for the accommodation of the latter.

As illustrated in solid line in Fig. 3, the holding tab 19 normally acts to restrain the tab 24 from

outward swinging from its normal closing position. However, the latching action is not so positive as to prevent removal of tab 24 if desired and outward swinging of the closure panel 25, and for this purpose the tab 24 carries an arcuate slit 28 defining a finger piece 29 adapted to be grasped by the user as an aid in manipulating said closure member. The interior of container 10 is then visible through the opening 20 in inner section 16 of the device and the window opening 11 of the container. When it is desired to restore the closure panel, it is only necessary to insert the end of the latching tab 24 in the holding recess behind tab 19, whereupon said panel is effectively restrained against inadvertent displacement.

I illustrate in dotted lines in Fig. 4 the position of the finger piece 29 when deflected outwardly for grasping and the manner of swinging panel 25 outwardly, as described above.

In Figs. 5, 6 and 7 a somewhat modified adaptation of the invention is illustrated, which is, however, fundamentally similar to the embodiments of Figs. 1 to 4; hence similar parts are designated by similar reference numerals. Here the latching tab 19 is omitted and in substitution therefor an aperture 30 is punched in section 15 immediately adjoining the slit 23 which outlines tab 24. As illustrated in Fig. 7, the parts are folded and applied to the container 10 in a manner identical to that described in connection with the first embodiment. The aperture 30 affords access for the user's fingernail in initially swinging the panel 25 outwardly, in the fashion illustrated in Fig. 7.

A still further modified form of the invention is shown in Figs. 8, 9 and 10. In this embodiment the device is of two-part construction, comprising an inner member 31 having rounded corners and end margins, but still generally rectangular in shape, which is die cut to provide an opening 32 centrally thereof, said opening conforming in outline to the opening 11 in the garment bag. Said member or section also has an arcuate slit 33 in outwardly spaced relation to the margin of opening 32 at one end of the latter; at the opposite side of said opening the member 31 is provided with an aperture 34, one side 35 of which parallels a slit 36 in the member in such manner as to define a flexible holding or retaining strap 37 immediately adjacent the aperture 34. A transparent window sheet 38 is adhesively secured to section 31 over opening 32.

The device is completed by a separate closure panel or flap 39 of rectangular shape, having side notches 40 which define an end pivoting tongue 41. The opposite margin of the panel 39 carries a laterally projecting latching tab 42.

In assembling the last described device, the tongue 41 of panel 39 is inserted through slit 33 of section 31 with the said panel externally overlying section 31 and laterally overlapping the margins of the window opening 32 in the latter. The shoulder notches 40 are placed in engagement with the ends of the slit 33 to provide a pivotal engagement of the panel relative to section 31. The rear surface of said section is then given a coating of adhesive and is secured to the container 10 in surrounding relation to opening 11 therein. This disposes the tongue 41 between the section 31 and the body of container. The closure panel 39 is secured in place over openings 32 and 11 by inserting the tab 42 inwardly into the aperture 34 and threading underneath the locking strap 37, in the manner clearly illus-

trated in Fig. 10. Tab 42 may be removed and replaced as many times as are desired, and when in place serves to retain panel 39 in effective, laterally overhanging and light-sealing relation to the aligned openings in section 31 and bag 10.

I claim:

1. In combination with a container having an apertured wall, a window device secured to said wall over the aperture thereof, comprising a pair of integrally and hingedly connected, superposed sections, one of which has an opening therein inwardly of its marginal edges in register with the wall aperture and the other of which is provided with a U-shaped slit defining a closure flap hinged between the ends of the slit, said flap being of an area substantially larger than the area of said opening to laterally overlap and light-seal said opening in a closed position of the flap, said flap being swingable outwardly about the hinge thereof to position for viewing through said opening, means integral with the last named section for latching the flap in said first named position, and a transparent window sheet adhesively secured to one of said sections in covering relation to said opening.

2. In combination with a container having an apertured wall, a window device secured to said wall over the aperture thereof, comprising a pair of integrally and hingedly connected, superposed sections, one of which has an opening therein inwardly of its marginal edges in register with the wall aperture and the other of which is provided with a U-shaped slit defining a closure flap hinged between the ends of the slit, said flap being of an area substantially larger than the area of said opening to laterally overlap and light-seal said opening in a closed position of the flap, said flap being swingable outwardly about the hinge thereof to position for viewing through said opening, and being provided with a terminal finger piece adjacent the free edge thereof, means integral with the last named section coacting with said finger piece in latching the flap in said first named position, and a transparent window sheet adhesively secured to one of said sections in covering relation to said opening.

3. In combination with a container having an apertured wall, a window device secured to said wall over the aperture thereof, comprising a pair of separate, integrally and hingedly connected, superposed sections, one of which is adhesively secured to said wall and has an opening cut therein inwardly of its marginal edges in register with the wall aperture, the other of which affords a swingable closure flap, said flap being of an area substantially larger than the area of said opening to laterally overlap and light-seal said opening and being swingable outwardly about the hinged connection thereof for viewing through said opening, and a transparent window sheet secured to one of said sections in covering relation to said opening.

4. In combination with a container having an apertured wall, a window device secured to said wall over the aperture thereof, comprising a pair of integrally and hingedly connected, superposed sections, one of which is adhesively secured to said wall and has an opening cut therein inwardly of its marginal edges in register with the wall aperture, the other of which affords a swingable closure flap, said flap being of an area substantially larger than the area of said opening to laterally overlap and light-seal said opening and being swingable outwardly about the hinged connection thereof for viewing through said opening,

a terminal finger piece on said flap adjacent the free edge thereof, means integral with the other section coacting with said finger piece to latch the flap in sealing position, and a transparent window sheet secured to one of said sections in covering relation to said opening.

5. In combination with a container having an apertured wall, a window device secured to said wall over the aperture thereof, comprising a pair of separate, integrally and hingedly connected, superposed sections, one of which is adhesively secured to said wall and has an opening cut therein inwardly of its marginal edges in register with the wall aperture, the other of which affords a swingable closure flap, said flap being of an area substantially larger than the area of said opening to laterally overlap and light-seal said opening and being swingable outwardly about the hinged connection thereof for viewing through said opening, a terminal finger piece on said flap adjacent the free edge thereof, means integral with the other section coacting with said finger piece to latch the flap in sealing position, and a transparent window sheet secured to one of said sections in covering relation to said opening.

6. A window device for a container of the type having an apertured wall, comprising a pair of integrally and hingedly connected, inner and outer superposed sections having aligned viewing openings positionable in register with the aperture of said container wall in the operative position of said sections, said outer section having a flap connected thereto which is of substantially larger area than the opening in said inner section and is positioned in overlapping relation to the margin of said last named opening, said flap being shiftable to a position in spaced relation to said openings, and a single transparent window sheet adhesively secured to both of said sections in covering relation to the respective openings therein.

7. A window device for a container of the type having an apertured wall, comprising a section having a window opening therein positionable in register with the aperture of said container wall and a further section including a closure flap in integrally hinged superposed relation to said first named section, which flap is of substantially larger area than said opening and is swingable into and out of position overlapping the margin of said opening; and means integral with said further section for securing said flap in said overlapping relation to said opening.

8. A window device for a container of the type having an apertured wall, comprising a pair of integrally and hingedly connected, inner and outer superposed sections having aligned viewing openings positionable in register with the aperture of said container wall in the operative position of said sections, said outer section having a flap integrally connected thereto which is of substantially larger area than the opening in said inner section and is positioned in overlapping relation to the margin of said last named opening, said flap being shiftable to a position in spaced relation to said openings, transparent window means adhesively secured to at least one of said sections in covering relation to the opening therein, and a tab integral with one of said sections and coacting therewith to provide a detent engageable with said flap to latch the latter in said overlapping relation.

9. A window device for a container of the type having an apertured wall, comprising a pair of

integgrally and hingedly connected, inner and outer superposed sections having aligned viewing openings positionable in register with the aperture of said container wall in the operative position of said sections, said outer section having a flap integrally connected thereto which is of substantially larger area than the opening in said inner section and is positioned in overlapping relation to the margin of said last named opening, said flap being shiftable to a position in spaced relation to said openings, a single transparent window sheet adhesively secured to both of said sections in covering relation to the respective openings therein, and a tab integrally connected to the margin of one of said sections 10 and foldable to overlying secured relation there-

to, said tab constituting a detent engageable with said flap to latch the latter in said overlapping relation.
